UNITED STATES PATENT OFFICE.

RUDOLPH C. KRUSCHKE, OF DULUTH, MINNESOTA.

GUARD FOR TROLLING-HOOKS.

1,178,861.

Specification of Letters Patent. Patented Apr. 11, 1916.

Application filed May 28, 1915. Serial No. 31,026.

To all whom it may concern:

Be it known that I, RUDOLPH C. KRUSCHKE, citizen of the United States, residing at Duluth, in the county of St. Louis 5 and State of Minnesota, have invented certain new and useful Improvements in Guards for Trolling-Hooks, of which the following is a specification, reference being had therein to the accompanying drawing.

10 This invention relates to guards for trolling hooks and has for its principal object the production of a simple and efficient means for protecting the hook against foreign objects, such for instance as eel- 15 grass, lily pads, snags and like objects when trolling for fish in waters wherein such obstructions are likely to be encountered.

Another object of this invention is the production of a guard for trolling hooks 20 which comprises a plurality of elongated resilient wires so formed as to extend for a considerable distance beyond the end of the hooks, thereby forming a continuous shank for the spoon or minnow and the 25 hooks, whereby the foreign objects will be prevented from clogging the operating portions of the device, the guard being formed so as to easily yield when struck by fish so as to allow the fish to come into engagement 30 with the hooks.

Another object of this invention is the production of a frame member which is adapted to carry a cork, this frame member being so constructed as to allow the 35 guard fingers to be positively held in engagement therewith, while the cork will act as a reinforcing element and positively retain the shank in engagement therewith.

With these and other objects in view, this 40 invention relates to certain novel combinations, constructions, and arrangements of parts as will be hereinafter fully described and claimed.

In the accompanying drawings: Figure 45 1 is a detailed perspective view of a guard as constructed in accordance with this invention. Fig. 2 is a vertical section through the upper portion of the device illustrating the manner in which the shank is supported. 50 Fig. 3 is a section taken on the line 3—3 of Fig. 2, looking in the direction of the arrows. Fig. 4 is a detailed perspective view of the principal portions of the device, the protector hood being removed. 55 Fig. 5 is a detailed perspective view of the upper portions of the guard illustrating

the manner in which the guard fingers are conducted to the frame, the cork being removed. Fig. 6 is a plane view of the blank from which the frame is formed. 60

Referring to the accompanying drawing by numerals it will be seen that the frame is constructed from a blank sheet of metal as clearly shown in Fig. 6. This frame comprises a base 1 having an elongated slot 65 2 formed in its central portion. Arms 3 and 4 extend from each side of the base 1 in alinement with each other in such a manner as to allow the arm 3 to be provided with the cap 5 formed integrally thereon. 70 These arms are adapted to be bent so as to extend upwardly, whereby the cap 5 may also be bent upon the arm 3 and thus extend in upward spaced relation relative to the base 1. The upper end of the arm 4 75 is adapted to be bent upon the scored line 6 so as to provide an overhanging lip 7, which fits upon the upper portions of the cap 5. This lip 7 is adapted to be soldered upon the cap 5 as shown at 8 in Fig. 4 80 thereby fixedly retaining the cap 5 in spaced relation relative to the base 1. This cap 5 of the arm is also provided with an elongated slot 9 which is formed to be positioned in alinement with the slot 2 of the 85 base 1 when the frame is assembled, as is clearly shown in Fig. 5. After the frame has been constructed as above set forth a cork filler-block 10 is interposed between the base 1 and cap 5 thereby assisting the arms 90 3 and 4 in retaining the base and cap in spaced relation so as to form a very rigid and substantial structure. This filler-block may, of course, be made of any other suitable material, and is provided with a vertical opening 11 extending therethrough so as to communicate with each of the slots 2 and 9 as shown in Fig. 2. It will, of course, 95 be noted that this vertical opening 11 of the filler-block 10 tapers at its lower end for 100 purposes to be hereinafter set forth.

The guard fingers which are formed of resilient wire have bent body portions curved throughout their entire length as shown at 12. The inner ends 13 of these 105 guard fingers are bent so as to extend in upward spaced relations, passing through the apertures 14 formed in the base 1 as well as the apertures 15 formed in the cap 5. These apertures 14 and 15 are formed so as 110 to be in alinement with each other, thereby allowing the inner ends of the guard fingers

to pass through one of the apertures 14 and one of the apertures 15. It will, of course, be noted that these guard fingers are adapted to pass through the filler-block 10 as shown in Fig. 3, whereby the filler-block will be positively retained in engagement with the frame. The upper ends of the guard fingers are bent so as to clamp upon the cap 5 as shown at 16, and in this manner prevent their being withdrawn from their correct position. It will, of course, be noted that the movement of the guard fingers upwardly is prevented since the fingers radiate immediately upon passing through the apertures 14 of the base 1 and this annular construction will limit or prevent the movement of the guard fingers upwardly. If it is so desired a quantity of solder 17 may be applied to the bent ends 16 of the guard fingers for positively retaining the guard fingers against any movement after the device has been assembled. Since the filler-block 10 is provided with flat side portions 18 which engage the inner surfaces of the arms 3 and 4, the filler-block will also be used in retaining the guard fingers against accidental movement. The shank 19 which carries the revolving spoon or minnow 20 by means of the sleeve 21 is provided at its inner end with an enlarged looped portion 22. This looped portion radiates toward its upper end so as to conform somewhat to the contour of the shape of the inner portion of the opening 11 formed in the filler-block 10 as shown in Fig. 2. Therefore, since the looped portion 22 tapers toward its lower portion, it will be positively retained in engagement with the filler-block 10 inasmuch as it will be impossible to withdraw the enlarged upper end 22 of the looped portion through the lower reduced end of the opening 11. The line 23 is attached to this looped portion and passed upwardly so as to allow the device to be pulled through the water. A hood 24 having open upper and lower ends is positioned upon the guard so as to fit upon the outer side portions of the filler block 10 as well as the frame, and in this manner the entire structure will be efficiently reinforced as well as protected from being injured by coming into contact with foreign objects. The shank 19 is adapted to carry the hooks 25 on its upper ends adjacent the spoon or minnow 20. The guard fingers 12 extend from the filler-block so as to pass for a considerable distance beyond the hooks 25, thereby forming a continuous guard for overhanging the spoon or minnow as well as the hooks. Therefore, when the device is in operation it will be seen that as the same is drawn through the water, the spoon will be rotated by the action of the water thereon, while the spoon as well as the hooks will be prevented from becoming

clogged or otherwise injured by coming into contact with foreign objects. It will be noted, however, that owing to the resilient construction of the guard fingers 12, when a fish swims thereagainst, the guard fingers 73 owing to their resilient construction will yield sufficiently to allow the fish to engage the hooks 25.

From the foregoing description, it will be seen that a very efficient guard has been 75 provided for trolling hooks, wherein the guard members extend continuously, so as to overhang the operating elements of the device, while the frame and filler-block are constructed so as to positively retain the 80 guard members and shank for the trolling elements in their correct positions so as to provide an operative structure which is capable of preventing foreign objects from 85 engaging the operating elements, but which will always allow the fish to come into engagement therewith.

What is claimed is:

1. In a device of the class described the combination of a frame, a filler-block carried by said frame, guard fingers carried by said frame and passing through said filler-block for anchoring the same in engagement with said frame, said filler-block provided with a vertical opening extending 90 therethrough, said opening tapering toward its lower portions, a shank provided with a looped portion fitting within said vertical opening in said filler-block, said looped portion radiating toward its upper end so as to conform substantially to the contour of said vertical opening, whereby when an outward strain is brought to bear upon said shank it will be prevented from accidentally dis-engaging the said filler-block, said shank 95 being adapted to carry a spoon or minnow and hooks, said guard fingers overhanging said shank and the operating elements carried thereby continuous and being curved throughout their entire length so as to prevent foreign objects coming into engagement therewith beyond the operating elements thereof, said fingers being adapted to easily yield so as to allow a fish access to the hooks carried by said shank. 115

2. In a device of the class described the combination of a frame formed from a blank and comprising a base, vertical arms formed upon said base, a cap formed upon one of said arms, the opposite arm being 120 provided with an extending lip for fixedly securing to said cap whereby the cap will extend in an upwardly spaced relation to said base, said cap and base being provided with registering longitudinal slots, a filler-block fitting within said base and cap for reinforcing the frame, a shank passing through slots and through said filler block, means for retaining said shank in engagement with said filler-block, said filler-block 125 130

being provided with flat side portions engaging the inner portions of said arms, whereby the block will be retained against rotation, and guard fingers carried by said frame so as to extend for a considerable distance therebeyond, said shank being adapted to carry a spoon and hooks whereby the said guard fingers may overhang the same so as to prevent foreign objects 10 from coming into engagement therewith and render the device inoperative when in use.

3. In a device of the class described the combination of a frame, a filler-block carried by said frame, a shank passing through said frame and being carried by said filler-block, said shank being adapted to be provided with a spoon and with hooks, guard fingers passing through said frame and 20 filler-block, means for retaining said guard fingers in position, and a hood fitting over said frame and filler-block so as to protect the same, said hood provided with an open end, and a line secured to said shank and 25 passing through said hood whereby the device may be drawn through the water when desired, said guard fingers being adapted to overhang said spoon and hooks of said shank, to prevent foreign objects from coming 30 into engagement therewith when the device is in operation.

4. In a device of the class described the combination of a block having an opening, a shank provided with a loop fitting within said opening, said loop conforming in shape 35 to the contour of said opening, whereby said shank will be held against accidental displacement, guard fingers carried by said block, said shank being adapted to carry a spoon and hooks, whereby said fingers will 40 overhang the same thereby preventing foreign objects from coming into engagement with the spoon and hooks.

5. In a device of the class described, the combination of a frame, said frame comprising a base and cap, means for connecting said base and cap, means for reenforcing said frame, a shank carried by said frame, said shank being adapted to carry a spoon or minnow and hooks, and guard 50 fingers carried by said frame, said fingers extending so as to overhang said shank for guarding the spoon or minnow and hooks, said fingers terminating in bent inner ends, said bent ends fitting upon said cap, said 55 fingers being bowed outwardly at a point adjacent said base, whereby longitudinal movement of said fingers upon said frame is positively eliminated.

In testimony whereof I hereunto affix my 60 signature.

RUDOLPH C. KRUSCHKE.
